(57) **CLAIM**

The ornamental design for a display screen with a graphical user interface, as shown and described.

DESCRIPTION

FIG. I is the first image in a sequence for a display screen with a graphical user interface;

FIG. 2 is a second image thereof;

FIG. 3 is a third image thereof;

FIG. 4 is a fourth image thereof; and,

FIG. 5 is a fifth image thereof.

The appearance of the animated image sequentially transitions between the images shown in FIGS. 1 through 5. The process or period in which one image transitions into another forms no part of the claimed design.

The outermost broken-line rectangle illustrates the perimeter of a display screen and forms no part of the claimed design. The remaining broken lines illustrate a graphical user interface and form no part of the claimed design.
